TWIN PORTABLE TUBS AND SUPPORTS
THEREFOR

Harvey E. Meyer, Kansas City, Mo.

Application April 2, 1941, Serial No. 386,483

2 Claims. (Cl. 68—232)

My invention relates to portable tubs, and more particularly to twin portable tubs.

It is highly desirable in connection with home laundry work to have a pair of tubs in close adjacency to each other, and it is also desirable to have the tubs portable. In order that the tubs could be placed closer together and more easily moved from place to place without tipping, it is desirable that the portable tubs be mounted in pairs so as to have common supporting means. While frameworks have been previously provided on which a pair of tubs was mounted in close adjacency, so that the same were fixed to the framework, a rather expensive framework was necessary in order to mount the tubs in pairs in such close adjacency, so that the same could be moved together as a unit. While single portable tubs have been previously provided, that were mounted directly on legs, so as to avoid the necessity of any additional framework, the advantage of mounting a pair of tubs on the same set of legs was largely lost, from an economy standpoint, because of the fact that additional framework was necessary to mount the pair of tubs on the legs, which made the cost of production of a pair of tubs so united to be movable about as a unit at least as great or greater than the cost of production of two separate portable tubs.

It is a purpose of my invention to provide twin portable tubs that are so constructed and mounted that the same can be produced very cheaply, all supporting framework under the tubs between the legs being dispensed with, and that are mounted firmly on the portable supporting means in fixed relation to each other, so as to bridge the space between the upper ends of the legs upon which the same are mounted, to provide portability therefor, in a manner to form a beam-like member made up of the tubs and the means fixedly securing the same together at their adjacent portions, which is strong and which will support all of the weight required of the structure with an ample factor of safety.

More particularly my invention comprises clamping means, mounted between the adjacent portions of a pair of tubs, securing the same together in fixed relationship so that the pair of tubs form a unit extending from one supporting means at the remote portion of one tub to the other supporting means at the remote portion of the other tub that is of sufficient strength and rigidity to support any load to which the same may be subjected in normal use.

It is a further purpose of my invention to provide a portable twin tub structure of the above

mentioned character, that is provided with supporting means comprising pairs of legs at remote ends of the pair of connected tubs, which legs are connected near their lower ends by means of bracing members that are angular in cross section and which are secured to the legs at one end of each thereof, and which are secured together at their other ends to unite the same at the junction points of the diagonal braces, firmly in fixed relation to each other, said bracing means and said legs and the clamping means, above referred to, being made up of members of such length that the same can be readily inserted within one of the tubs of the pair and the tubs nested so as to make a compact package for shipment from the place of manufacture to the place of use or sale, and providing a package that can be shipped at a much lower freight rate than tubs mounted on a frame which must be left set up, or partly set up, in such a manner as to provide a much less compact package, requiring a higher freight rate.

Other objects and advantages of my invention will appear as the description of the drawings proceeds. I desire to have it understood, however, that I do not intend to limit myself to the particular details shown or described, except as defined in the claims.

In the drawings:

Fig. 1 is a perspective view of my invention as arranged for use in connection with what are commonly known as "square" tubs.

Fig. 2 is a similar view, partly broken away, showing my invention as used in connection with what are commonly referred to as "round" tubs.

Fig. 3 is a vertical sectional view on an enlarged scale through the clamping means utilized in Fig. 1, showing fragmentary portions of the tubs with which the clamping means engage.

Fig. 4 is a top plan view of the lower plate of the clamping means shown in Fig. 3, taken on a somewhat smaller scale than Fig. 3.

Fig. 5 is a top plan view of the upper plate, or bar, of the clamping means shown in Fig. 3, taken on the same scale as Fig. 4.

Fig. 6 is a section taken on the line 6—6 of Fig. 4, on an enlarged scale.

Fig. 7 is a section taken on the line 7—7 of Fig. 5, on an enlarged scale.

Fig. 8 is a fragmentary section through the top clamping means and the square tubs engaged thereby.

Fig. 9 is a view similar to Fig. 4, of the bottom clamping plate utilized in conjunction with round tubs.

Fig. 10 is a view similar to Fig. 5 of the top

clamping plate utilized in conjunction with round tubs.

Fig. 11 is a section taken on the line 11—11 of Fig. 9, on an enlarged scale.

Fig. 12 is a section taken on the line 12—12 of Fig. 10, on an enlarged scale.

Fig. 13 is a fragmentary section through the top clamping means and the round tubs engaged thereby.

Fig. 14 is a detail horizontal sectional view of means for securing the adjacent ends of the diagonal bracing means to each other.

Fig. 15 is a fragmentary section taken on the line 15—15 of Fig. 14, the securing element being shown in elevation.

Fig. 16 is a fragmentary detail view, partly in horizontal section, of the connection between the bracing means and the legs, and

Fig. 17 is a vertical sectional view through the annular body portion of one of said bracing members.

Referring in detail to the drawings, in Fig. 1 is shown a pair of tubs 21 and 22, which are identical in shape and size, and which are what is commonly known as "square" tubs. As is obvious, said tubs have inclined sides, so that the bottom portion thereof is somewhat smaller than the top portion thereof, and ordinarily such tubs are provided with beads 23 running around the top thereof, that may be made in any desired manner, and which follow the contour of the tub at its top edge. While these tubs are referred to as "square" tubs, the same are not actually square, but have straight side portions 24, that are connected with each other by means of curved portions 25, the beads, of course, having similar straight and curved portions.

Said tubs are arranged with one of the straight side faces of one thereof in adjacency with the straight side face of the other tub, and are provided with legs 26 at the ends, or portions thereof that are remote from those portions that are adjacent each other, said legs being provided substantially at the rounding corner portions 25 that are remote from the adjacent sides of said tubs. The legs 26 diverge slightly away from each other in all directions, so as to provide greater stability for the unit made up of the portable unit comprising the pair of tubs, with, of course, the lower ends thereof more widely spaced from each other than the upper ends thereof. The upper ends of the legs are secured, by any suitable clamping means 20, to the tubs adjacent the bottoms thereof, this clamping means not forming a part of this invention and being well known, the flanges depending from the bottoms of said tubs, which are shown at 27 in Fig. 3, being utilized to clamp the legs to the tubs, it being obvious that the clamping means can be readily engaged with shoulders formed by means of said flanges, so as to fix the legs to the tubs in depending diverging relation, as above referred to.

In order to dispense with all the underframes for the tubs and to make the tubs self-supporting on said legs, I provide clamping means for fixedly securing the adjacent portions of the tubs to each other so that the tubs will form a rigid bridging or beam-like member in conjunction with said clamping means, extending from one pair of legs 26 at one end of the unit to the other pair of legs 26 at the other end of the unit. Said clamping means for the so-called "square" tubs is shown more in detail in Figs. 3, 4, 5, 6, 7 and 8, and comprises a lower clamping plate 28, which has flanges 29 thereon projecting upwardly from the longi-

tudinal edges of said clamping plate, said clamping plate having curved edged enlargements at the opposite ends thereof and said flanges having curved portions 30 that extend along the edges of said curved edged enlargements, so as to follow the contour and interfit with similarly curved portions on the depending flanges 27 on the tubs 21 and 22. The straight portions of the flanges 29, of course, fit the straight portions of the flanges 27 that lie at the bottom edges of the straight walls 24, and the curved portions 30 of the flanges follow the contour of and engage the curved portions of the flanges 27 lying at the bottom edges of the curved wall portions 25 of said tubs that are adjacent each other. Thus the bottom plate 28 is mounted in interfitting relation to the bottoms of the adjoining tubs, with the flanges 29 and 27 in inter-engagement with each other, so as to prevent any tendency of the tubs 21 and 22 to separate at their bottom edges. Also any tendency of the tubs to get out of transverse alignment with each other is avoided, due to the curved flange portions 30 cooperating with the correspondingly curved flange portions depending from the tubs 21 and 22.

Said clamping means further comprises a top clamping plate 31, which is substantially channel-shaped in cross section, with straight parallel flanges 32 depending therefrom throughout the major portions of their length and engaging the inner sides of the straight portions of the beads 23 at the top edges of the walls 24 of the tubs 21 and 22 that lie adjacent each other. Said top clamping plates 31 are provided with end enlargements having curved side edges 33 that have curved portions 34 of the flanges 32 depending therefrom, said curved flange portions 34 engaging the inner sides of the curved portions of the beads 23 in a manner clearly evident from Figs. 1 and 8. Referring to Figs. 5 and 8 it will be noted that the enlarged ends 33 have offset portions 43 therein defining diverging curved grooves 19, receiving the beads 23 therein at the curved top edge portions of the tubs. All tendency for the tubs to get out of alignment with each other longitudinally of the clamping plate 31 and to move toward each other is avoided, due to these curved grooves 19 thereon that engage said beads 23 at the curved portions thereof to prevent any shifting of the tubs relative to the clamping plates 31 lengthwise and transversely of said clamping plates, the flanges 32 on the plates 31 preventing any separation of the tubs and the clamping plates and tubs thus being fixed relative to each other.

The clamping plates 28 and 31 are provided with openings 35 and 36, respectively, that align with each other, through which the headed screw-threaded securing elements 37 extend to firmly clamp the plate-like members 28 and 31 to the tubs and thus rigidly fix the tubs to each other at their adjacent portions, said fastening elements 37 being made in the form of long headed rod-like members receiving the nuts 38 on the screw-threaded ends thereof.

The clamping plates 28 are, preferably, provided with a plurality of transverse stiffening formations 39 and a plurality of longitudinal stiffening flanges 40, and with transverse stiffening flanges 41 along their opposite end edges. The wide end portions of the clamping plates 31 are also provided with stiffening flanges 42, similar to the flanges 41, and the offset portions 43, in which the openings 36 are located. The

flanges 42, of course, terminate short of the edges 33 so as to permit the insertion of the clamping plates 31 into cooperative relation with the beads 23 along the top edges of the adjacent sides of the tubs.

The legs 26 are, of course, provided with casters 44, which are mounted in any desired manner, as with the upstanding stem portions thereof mounted in openings 45 in the legs, such as shown in Fig. 16. Adjacent the bottom ends of the legs 26 bracing members are provided, comprising the transverse bracing members 46 and the obliquely or diagonally extending bracing members 47. The bracing members 46 and the bracing members 47 are all made angular in cross section, as illustrated for the one bracing member 47 in Fig. 17. However, the ends thereof are flattened, as shown at 48 in Figs. 14, 15 and 16, and said flattened ends 48 of a diagonal bracing member 47 and of a transverse bracing member 46 are secured to each leg 26 in the manner shown in Fig. 16, the flattened portions 48 being perforated to receive the headed screw-threaded securing element 49, and the leg portions 26 being shaped so as to become substantially U-shaped in cross section at their lower ends for receiving the flattened end portions 48 of the braces 46 and 47 between the parallel leg portions of said U-shaped portion of said leg.

Four of the members 47 comprise a diagonal bracing means, and these are secured together at their meeting ends in the manner shown in Figs. 14 and 15, said members being made in this manner and secured together at their junction so that the entire portable tub device can be readily compactly packed for shipment. The tub 21 can be nested in the tub 22, or vice versa, when these are separate, such as when the clamping means are not in place, and all the parts, including the legs 26, upon release of the clamping means 20, the braces 46, the braces 47, and the clamping means 28, 31 and 37 can be placed within one of the nested tubs, the same being all of such length as to be no greater than the greatest diameter of the tub 21 or 22.

The means for securing the adjacent ends of the diagonal braces 47 together comprises a pair of channel members 50, which are arranged back to back, and which have flaring or diverging flanges 51, thus providing tapering grooves, having their narrowest transverse dimension at the bottoms thereof, on opposite sides faces of said clamping means. Said channel-shaped members 50 can be permanently secured together back to back, if desired, or can be made as shown in Fig. 14, in which each of said channel-shaped members has a lug 52 struck out from the material of said member, which engages in a slot 53 of the other of said members, so as to hold said pair of members 50 from any longitudinal movement relative to each other, any other suitable means for preventing such longitudinal movement being also usable, of course, but the particular means shown being economical in manufacture and cheap, while serving the purpose satisfactorily. The flattened end portions 48 of said bracing members 47 are mounted in the grooves formed between the flanges 51, and the screw-threaded headed fastening elements 54 are passed through aligning openings in the flattened portions 48 and channel members 50, and tightened up to firmly clamp the flattened ends in the tapering grooves formed by means of the flanges 51, to thus firmly fix the diagonal bracing

members 47 to each other at their junction and form a substantially X-shaped unitary brace thereof extending from one pair of legs 26 to the other pair of legs 26.

5 In Fig. 2 my invention is shown as modified for use in connection with round tubs. The legs 26 are secured in the same manner as previously described and are provided with similar bracing means to those shown in Fig. 1, and these accordingly are not again shown, said legs being secured in a similar manner to that previously referred to. The tubs 21' and 22' are provided with a circular top edge that has the bead 23' thereon and flanges 27', similar to the flange 27, depend from the rounded bottoms of the tubs, said tubs flaring upwardly in a similar manner to that of the square type of tub shown in Fig. 1, as will be obvious from Fig. 2.

A bottom clamping plate 28' and a top clamping plate 31', secured together by means of the headed screw-threaded securing members 37, are provided for fixedly securing the adjacent portions of the tubs 21' and 22' to each other. The clamping plates 28' and 31' are shown more in 10 detail in Figs. 9, 10, 11, 12 and 13. Said clamping plate 28' has a pair of concavely curved edge portions, which are provided with upstanding curved flanges 55, which are curved on the same arc as the depending peripheral flanges 27' on 15 the tubs 21' and 22' and fit around these in a similar manner to the flanges 29 and 30, previously described in connection with Figs. 1, and 20 3 to 8, inclusive. Stiffening formations 39', similar to the formations 39, and openings 35 are provided, as in the form of the invention previously 25 described, and longitudinal stiffening formations 40' are provided, which are similar to the formations 40 described in connection with Figs. 3 and 4. Depending end stiffening flanges 41' 30 are also provided, said stiffening formations and flanges being similar to those previously described, except that the same are of different contour and length.

The top clamping plate 31' is also provided with 35 a pair of concave side edges 56, which have depending flanges 57 thereon, following the contour of said edges 56 and being curved on the same arc as the beads 23' at the top edges of the tubs 21' and 22'. Said clamping plate is also 40 provided with the end flanges 42', similar to the flanges 42, for stiffening the same, and with offset portions 43', said offsets 43' and flanges 57 defining curved grooves 19' receiving the beads 23' therein to hold the tubs in fixed position relative to said top plate 31'. The clamping plates 31' have the openings 36 in said offset portions 43' in a similar manner to that described in connection with the form of the invention shown 45 in Figs. 3 to 8, inclusive. It is, of course, obvious that when the clamping plates 28' and 31' are clamped in position by means of the screw-threaded headed fastening elements 37, the same will rigidly secure the tubs 21' and 22' in 50 fixed position relative to each other, so that the same will not shift lengthwise of the members 31' and 28' nor transversely thereof. It will also be obvious that the tubs 21' and 22' can be nested in a similar manner to the tubs 21 and 22 and the various parts of the clamping 55 means for connecting the tubs, the braces, and the legs, nested within one of said tubs so as to 60 make a compact package for shipping.

What I claim is:

1. In a portable tub structure, tubs, and means 65 for supporting said tubs comprising legs on which

said tubs are mounted and diagonal braces connecting said legs to form a framework having said legs projecting upwardly from the corners thereof, said braces comprising a plurality of members of angular cross section having flattened ends, means for securing one of said flattened ends of each of said members to a leg and clamping means for securing the other flattened ends of all said legs together, comprising a pair of channel-shaped members arranged back to back, means for holding said channel-shaped members against relative longitudinal movement and means for clamping said other flattened ends in the channels of said members.

2. In a tub support of the character described, a framework comprising pairs of spaced upstanding legs and means preventing the separation of

said legs at the lower ends thereof, comprising diagonal braces connecting said legs, said braces comprising a plurality of members of angular cross section having flattened ends, means for securing one of said flattened ends of each of said members to a leg and clamping means for securing the other flattened ends of all said legs together, comprising a pair of channel-shaped members arranged back to back, means for holding said channel-shaped members against relative longitudinal movement and means for clamping said other flattened ends in the channels of said members, said channel-shaped members having flaring flanges with which said ends have wedging engagement.

HARVEY E. MEYER.
